US00D612671S

(12) **United States Design Patent**
Sanchez et al.

(10) **Patent No.:** **US D612,671 S**
(45) **Date of Patent:** **** Mar. 30, 2010**

(54) **SLEEVE FOR CIRCULAR ICE CHEST**

(75) Inventors: **Gregory Joseph Sanchez**, Gilbert, AZ (US); **Troy Allen Goins**, Gilbert, AZ (US)

(73) Assignee: **Cooler Concepts, LLC.**, Tempe, AZ (US)

(**) Term: **14 Years**

(21) Appl. No.: **29/337,454**

(22) Filed: **May 21, 2009**

(51) **LOC (9) Cl.** **07-02**

(52) **U.S. Cl.** **D7/392; D7/624.2; D7/608**

(58) **Field of Classification Search** **D7/300, D7/306, 313, 387, 392, 397, 450, 601, 603, D7/605, 606, 607, 608, 610, 624.1, 624.2, D7/625; D9/444, 711; D23/262, 266; D24/129; 62/457.4, 457.7, 530; 206/459.5; 215/392, 215/393, 395; 220/62.12, 315, 403, 677, 220/694, 737, 739**

(57) **CLAIM**

The ornamental design for a sleeve for circular ice chest, as shown and described.

DESCRIPTION

FIG. 1 is an isometric view from the front, left and top of a sleeve for a circular ice chest showing my new design, the broken lines depicting an ice chest form no part of my design;

FIG. 2 is a top view thereof;

FIG. 3 is an isometric view from the front, left and top thereof;

FIG. 4 is a bottom view thereof;

FIG. 5 is a left side elevational view thereof, the right side elevational view is a mirror image; and,

FIG. 6 is a front elevational view thereof.
